UNITED STATES PATENT OFFICE.

EDWARD M. HEWLETT AND CHARLES C. BADEAU, OF SCHENECTADY, NEW YORK, ASSIGNORS TO GENERAL ELECTRIC COMPANY, A CORPORATION OF NEW YORK.

CIRCUIT-BREAKER.

SPECIFICATION forming part of Letters Patent No. 745,348, dated December 1, 1903.

Application filed April 27, 1901. Serial No. 57,672. (No model.)

To all whom it may concern:

Be it known that we, EDWARD M. HEWLETT and CHARLES C. BADEAU, citizens of the United States, residing at Schenectady, county of 5 Schenectady, State of New York, have invented certain new and useful Improvements in Circuit-Breakers, of which the following is a specification.

This invention relates to automatic circuit-breakers, the object being to produce an instrument that will open circuits of high potential with safety and minimum damage to the contacts.

In carrying out the invention we provide a 15 pivoted iron-clad tripping-magnet or solenoid mounted to swing to and from the support and to be latched in position when the circuit is closed, so that in opening the combined effect of gravity and an assisting spring will 20 act upon the movable contacts to open the circuit. The operating mechanism is mounted between the main and shunt contacts, leaving all metal parts when the circuit is open with a wide clearance between contacts, thus 25 preventing possible short circuits from arcing. The movable system carries a bridging-contact for the main terminals and cramps a toggle when set, and the shunt-contacts are so arranged that in opening the pressure 30 upon the shunt-contacts is increased at the time of opening the main contacts to prevent arcing across the latter from differences of ohmic resistance in the two paths.

The novel features of the invention will be 35 more particularly hereinafter described, and will be definitely indicated in the claims.

In the accompanying drawings, illustrating the invention, Figure 1 is a side elevation of a circuit-breaker embodying my improvements. Fig. 2 is a partly-sectional elevation 40 showing the circuit-breaker in open position, and Fig. 3 is a front elevation of a circuit-breaker.

1 represents a supporting-board, of slate, 45 marble, or similar non-conducting fireproof material, upon which are mounted main and shunt terminals 2 and 3, respectively, a pair of each being provided. When the circuit is closed, the main contacts are bridged by 50 phosphor-bronze brushes formed of a bundle

of thin laminæ, as indicated at 4, two of these being placed in a line and mounted in a brass casting 5. The contacts 4 are in electrical connection each with an end of an operating-coil, one end of the leading conductor of which 55 is seen at 6. The coil is formed of a copper ribbon or bar spirally wound, with an intervening layer of paper, and consists of two sections 7 7^a, the inner ends being connected together by a brass tube lined with fiber and 60 the coils reversely wound with a separating-washer of fiber 8. The free ends of the coil are connected in the sockets 5, which carry the laminated contacts. Thus current passes from one terminal 2 through the laminated brush, through both coil-sections in series, to the other brush and out at the other main terminal, which is in the same horizontal plane as the terminal 2 and back of it, as represented in the drawings. By reason of the reverse winding of the two coil-sections the passage of current through them in series makes them act together in magnetizing effect upon the magnetic circuit. This circuit is completed by an iron core 9, nesting 75 in its retracted position in a brass tube 10, screwed to the frame, so that its axis coincides with that of the coils. The tube is threaded inside and provided with an adjustable plug 11, which may be placed at various positions in the tube to control the load at which the instrument will act and will be locked in such position by means of a setscrew 12, engaging two jaws of the plug formed by making a saw-cut partly through 80 it in a direction transverse to its axis. The core is of such a length that its upper end will enter part way into the coils. The casing is formed of cast-iron and forms a complete magnetic environment for the coils 90 closed on all sides, thus lowering the magnetic resistance and protecting the coils. In setting the coils in position in this casing they are guarded against contact with the frame by washers of fiber, as indicated in 95 Fig. 2, and the spaces between the coil and frame are filled with a mixture of Portland cement, the moisture being expelled by baking after the cement is set. The coil-casing is pivoted on its outer side above the center 100

in a supporting-bracket 13, so as to throw the center of gravity of the movable system to one side when the circuit-breaker is set, from which it results that when free to swing the 5 coil and its casing will shift outwardly, so as to bring the center of gravity of the system in line with the center of the pivot, a position of the parts depicted in Fig. 2. To assist the rapidity of this action, a stout coil-spring 10 14 is provided, having one end anchored on the bracket and the other in the coil-casing. An insulated handle 15 is secured to the outer side of the coil-casing to permit hand-setting. The handle and coil thus form a 15 single moving part.

In the upper part of the coil-casing is mounted a loose brass pin 16, supported by a shoulder in a hole bored in the top of the casing, the lower end projecting into the coil. This 20 pin co-operates with a bent lever 17, the top of which when the circuit-breaker is set pushes against the push-pin 16 or in close relation to the same. This lever is pivoted on a bracket or lug forming part of the coil-casing 25 and is connected with a pivoted link 18, journaled on a standard or lug projecting from the base of the bracket 13. This link and the bent end of the lever 17 form a toggle which locks the parts when straightened out to the position 30 shown in Fig. 1 and which collapses when tripped and permits the parts to assume the position shown in Fig. 2. The toggle may be collapsed by the automatic action of the device or by means of a pendulous rod of wood 35 19, pivoted at 18. In collapsing the toggle automatically the coil upon definite overload (determined by the position at which the plug 11 is set) lifts the core 9 with a rapidly-accelerating movement, accumulating momentum 40 until it strikes the pin 16, which under the impact of the blow pushes upward the lever 17 and collapses the toggle. The weight of the parts and the coacting spring 14 then shift the coil system to the open position, in doing which the bridging contacts 45 4 are first lifted from the main contacts 2 and then the shunt-contacts opened. The shunt-contacts are mounted on steel rods 20, pivoted concentrically with the link 18 and connected 50 to the moving frame by links 21 at 21^a, the end connected to the frame being on a slightly-higher plane than that fastened to the contact-arm. The coil-frame and link 21 thus constitute a second toggle, which controls 55 the movement of the shunt-contacts 22, and by reason of the position of the link 21, just described, when the main contacts are opened the first effect will be to put greater pressure upon the shunt-contacts 22, since 60 the parts in swinging throw the higher end of the link 21 down, thereby pushing in on the pivoted arm carrying the shunt-contact and producing a hard spring-pressure, which reduces the contact resistance, thereby lowering 65 the potential drop, and thus contributing materially to prevent pitting of the main contacts.

70 contacts. No claim is herein made to this feature, as it is the sole invention of Edward M. Hewlett. The shunt-contacts may be formed of copper or copper and carbon, preferably both, the fixed contact being provided with a copper part 3 and a carbon part 3^a in the spring-clip 3^b, all secured together and mounted on the shunt-terminal, which may be connected with the main terminal on the rear of the board by a copper bar 23. The bracket supporting the movable system is mounted between the main and shunt contacts, thus leaving all metal parts well clear of the arcs when the circuit is being opened 75 and when it is closed preventing leakage or the formation of arcs due to leakage.

In setting the circuit-breaker the handle 15 is pressed toward the base, shifting the main and shunt contacts together and straightening out the toggle, so that its centers are in line, thereby preventing its collapse until released by hand or automatic action, as hereinbefore described.

What we claim as new, and desire to secure 90 by Letters Patent of the United States, is—

1. A circuit-breaker having a pivoted tripping-coil adapted to swing outwardly from the base when the circuit-breaker is tripped, and main and shunt contacts on opposite sides 95 of its axis.

2. A circuit-breaker having a pivoted tripping-coil adapted to swing outwardly from the base when the circuit-breaker is tripped, contacts mounted relatively close to the base, 100 a toggle to hold the contacts set, and means carried by the coil for tripping the circuit-breaker.

3. A circuit-breaker having a tripping-coil rigid with the operating-handle, contacts operated thereby, and a toggle operated by the handle to set the circuit-breaker.

4. A circuit-breaker having a tripping-coil carried by the operating-handle pivoted above its center of gravity to swing outwardly from 110 the base when released, contacts mounted relatively close to the base, means for locking the contacts when set, and a releasing device governed by the coil.

5. A circuit-breaker having a tripping-coil 115 carried by the operating-handle pivoted to swing outwardly from the base, separately-pivoted main and shunt contacts mounted relatively close to the base, and having means for locking the contacts in position when set, 120 and a movable core supported along the coil-axis to trip the circuit-breaker.

6. A circuit-breaker having a pivoted tripping-coil, a toggle connected therewith, one link of the toggle having a projecting arm, a 125 trip-pin in line with the projection, and a core for operating the trip-pin.

7. A circuit-breaker having its operating-coil composed of a plurality of spirals 130 reversely wound and connecting at contiguous ends in series relation to conspire in magnetizing effect.

8. A circuit-breaker having a pivoted operating-coil, and main and shunt contacts on opposite sides of the same, the movable shunt-contact being carried on elastic arms cramped 5 when the circuit is closed.

9. A circuit-breaker having main and shunt contacts having engaging faces in substantially the same plane when the circuit is closed, and means for shifting them one after

another in opposite directions toward a normal to said plane.

In witness whereof we have hereunto set our hands this 25th day of April, 1901.

EDWARD M. HEWLETT.
CHARLES C. BADEAU.
